UNITED STATES PATENT OFFICE.

LANSING ONDERDONK, OF NEW YORK, N. Y., ASSIGNOR TO THE UNION SPECIAL
MACHINE COMPANY, OF CHICAGO, ILLINOIS, A CORPORATION OF ILLINOIS.

OVERSEAMING MACHINE.

1,109,455.

Specification of Letters Patent.

Patented Sept. 1, 1914.

Original application filed June 4, 1901, Serial No. 63,078. Divided and this application filed July 12, 1906.
Serial No. 325,916.

To all whom it may concern:

Be it known that I, LANSING ONDERDONK, a citizen of the United States, residing at New York, in the county of New York, State 5 of New York, have invented certain new and useful Improvements in Overseaming-Machines, of which the following is a description, reference being had to the accompanying drawing and to the letters and figures 10 of reference marked thereon.

The present invention relates to new and useful improvements in work supports for sewing machines, and more particularly to overseaming machines.

15 An object of the invention is to provide a machine of the above character which may be used for stitching small tubular articles.

In the drawings, Figure 1 is a perspective view showing a portion of the cloth plate 20 of an overseaming machine, also showing the projecting throat plate, or work support, and the support for the fabric and operator's hand; Fig. 2 is a detail in perspective of my improved throat plate.

25 This application is a division of my Patent #829,349, granted August 21, 1906, and reference may be had thereto for a description of the general features of a machine to which the present improvement is applied.

30 Referring to the drawings, my invention consists of a cloth plate 17, which terminates substantially in the line of feed, and which is provided with a throat plate 7. This throat plate is attached to the cloth plate

35 in any suitable way and is provided with an outwardly projecting curved portion forming a projecting horn or work support over which tubular articles to be stitched may be placed. This throat plate 7 is pro-

40 vided with an opening 8, which allows the passage of the looper from below the cloth plate up over the edge of the cloth plate, so that the edge of the fabric being sewed may be overseamed. This throat plate has

45 the usual openings for the passage of the needle and the feed dogs. Said throat plate is also formed with a passage for the trimming member, which co-operates with the lower stationary trimmer blade 10, attached

50 to the cloth plate. The throat plate is also formed with a rearwardly projecting tongue 14, over which the stitches are laid. A guide 15 is attached to the cloth plate 17, and oper-

ates to deflect the trimmed off strip. The front 12 of the throat plate is shown milled 55 out or depressed below the level of the part in rear of the needle, in order that the front of the feed dogs may catch the material and feed it forward before the rear portion of the feed dogs catch hold of the material, and 60 thus prevent puckering of the goods. This throat plate projects beyond the body of the cloth plate and is substantially narrow and rounded so as to form a flat horn or work support 11, over which small tubular articles, such as cuffs of shirts, may be slipped. This permits the machine which is formed with a flat cloth plate to accomplish the 65 functions of a machine having a cylindrical bed plate, and yet at the same time, be capable of stitching articles which are not tubular and which it is desired to support on a flat work support to facilitate the handling of the same. Attached to the cloth plate, and extending in a plane beneath the 70 projecting throat plate, is a supporting plate 5. This supporting plate extends from front to rear and is upwardly curved at the rear end, while the forward free corner thereof is bent downwardly, as at 6. This plate, being below the throat plate of the machine, is adapted to hold the work or body of the goods, and also serves as a rest for the hand of the operator. The downwardly projecting part 6 is for the purpose of preventing 75 the catching of the goods on the corner of the plate.

It will be noted from the above description that the end of the projection 11, serves 80 as a work support for the small tubular articles, and that said work support has a rounded-off, or cut-away portion extending to a point substantially in the rear of the feed slots. This cut-away portion, in operating upon tubular articles, assists materially in the manipulation of said articles. In order that the material may be freely 85 fed over the projecting horn or work support, it is necessary that said tubular articles be carried down at the rear edge of the work support as soon as possible after leaving the feed. The feed of the machine, or the operator, in pulling small tubular articles around the horn of the work support, draws the same against this rounded-off edge, or cut-away portion, and the material is crowded 90 100 105

forward along said rounded-off edge, which causes the material to pass around the horn in the shortest path possible, and thus give the greatest amount of available working slack to the material.

While I have shown the projecting horn or work support formed on the throat plate, it will be obvious that from certain aspects of the invention, this projecting horn may 10 be otherwise formed, the essential feature being the relatively small projecting part which serves as a horn or work support, around which the goods may be passed.

Having thus described my invention, what 15 I claim as new and desire to secure by Letters Patent, is:—

1. A work support having a feed slot therein, and a relatively small projecting portion, around which small tubular articles 20 may be fed, said work support having a cut-away portion extending to the rear of said feed slot, whereby said tubular articles, by contact with said cut-away portion are stripped from the work support after passing 25 the feed.

2. A work support having a feed slot therein, a needle opening and an opening therein extending substantially at right angles to the feed slot for the operation of 30 an over-edge thread carrying implement, said work support having a relatively small projecting portion, around which small tubular articles may be placed, said projecting portion being cut-away from a point 35 substantially in the rear of the feed slot toward the front of the machine, whereby tubular articles by contact with the cut-away portion, after being stitched, are deflected from the line of feed, toward the front of

the machine, so that very small articles may 40 be stitched.

3. In a sewing machine the combination with a cloth plate, a projecting horn or work support carried thereby, and a cloth support located in a plane below the horn for 45 supporting the body of the fabric, and the hand of the operator, while a portion of said fabric is being manipulated on the horn.

4. In a sewing machine the combination with a flat cloth plate, a projecting horn carried by the cloth plate and extending beyond the edge thereof, whereby tubular articles may be placed over said horn, said horn having feed slots therein, and being 50 cut-away from a point in rear of the feed 55 slots toward the front of the machine.

5. In a sewing machine, the combination with a cloth plate, a throat plate secured to said cloth plate, and projecting therefrom, a plate extending in a plane below said 60 throat plate, and having a downwardly turned portion at the forward end therefor.

6. In a sewing machine, a throat plate having a body portion adapted for attachment to the cloth plate, and a horn or projection extending beyond the body portion, said projection having openings formed 65 therein for the feed dogs and for the needle, the forward portion of said throat plate in advance of the needles being depressed below the plane of the rear portion thereof.

In testimony whereof I affix my signature, in presence of two witnesses.

LANSING ONDERDONK.
